RAILWAY TRAFFIC CONTROLLING APPARATUS

John M. Pelikan, Chicago, Ill., assignor to The Union Switch and Signal Company, Swissvale, Pa., a corporation of Pennsylvania

Application August 5, 1942, Serial No. 453,663.

10 Claims.

(Cl. 246—39)

My invention relates to railway traffic controlling apparatus, and it has particular reference to the organization of such apparatus into traffic controlling systems of the type in which code impulses of energy transmitted over either or both line and track circuits are utilized for effecting a control or controls.

In systems utilizing code impulses of energy, energy supplied to a pair of conductors of a control circuit is caused to be periodically interrupted or coded in one or another of a plurality of distinctive manners each comprised of different patterns of alternate "on" and "off" periods during which current does and does not flow, respectively. This coded current is detected, translated and utilized for establishing control of traffic governing signals, and generally such energy is constantly applied to a circuit even though it is necessary to control a signal only when a train is approaching thereto. There is, therefore, no particularly useful function for the current that is supplied to the control circuit during the interval that a train does not approach the signal. In certain applications, particularly where there is a limited supply of power as in territories where primary batteries are the only available sources, it is deemed desirable to conserve the power as much as possible by using it only when absolutely needed. My invention has for an object the provision of a novel and improved railway signal system incorporating normally deenergized control circuits of the coded current class. More particularly, an object of my invention is the provision of a novel and improved form of railway traffic controlling systems incorporating normally deenergized track circuits which operate on the self-generating code principle disclosed in my copending application, Serial No. 443,240, filed on May 16, 1942, for Railway traffic controlling apparatus.

Another advantage of a signal system incorporating coded track circuits which operate on the normally deenergized principle is that the life of the operating elements is extended by avoiding all unnecessary operations of the code following and code transmitting apparatus. Another object of my invention is the provision of a novel and improved railway traffic controlling system incorporating coded track circuits in which the life of the code operating and operated elements of the system is greatly increased.

A further object of my invention is the provision of a novel and improved railway traffic controlling system incorporating normally deenergized track circuits and having means for

approach lighting the signals governing traffic on the signaled stretch.

An additional object of my invention is the provision of a novel and improved railway traffic controlling system incorporating apparatus arranged to utilize a minimum of power.

Another object of my invention is the organization of railway traffic controlling apparatus into a novel and improved form of railway signal system.

The above-mentioned and other important objects and characteristic features which will become readily apparent from the following description, are attained in accordance with the invention by providing each of a plurality of sections of track with track circuit apparatus arranged on the self-generating code principle of my copending application, Serial No. 443,240. The apparatus of these sections is arranged to be normally deenergized and each section has associated therewith means effective to supply energy when a train approaches its associated section. These means include a stick relay which has an approach controlled pick-up circuit made effective when a train approaches, and a stick circuit that is effective when the section is occupied to maintain the energy available in the section. After the section becomes vacant, the available energy functions to deenergize the stick relay and restore the track circuit apparatus to its normal condition.

I shall describe one form of apparatus embodying my invention, and shall then point out the novel features thereof in claims.

35 Figs. 1A and 1B taken together with Fig. 1A on the left is a diagrammatic view showing apparatus embodying my invention.

In the drawings, apparatus embodying my invention is represented applied to a stretch of 40 single track railway over which traffic normally operates in the eastbound direction indicated by an arrow pointing from left to right as viewed in the drawings. The track rails 1 and 1a of the stretch are divided by the usual insulated joints 45 2 into a plurality of successive adjoining track sections, of which four sections are shown, namely, sections D—E, E—F, F—H and H—J. Each of these sections is provided adjacent its entrance end with a traffic controlling wayside 50 signal, designated by the reference character S with a suitably distinguishing prefix. These signals may be of any suitable type, but for the purpose of the present description it will be assumed that the signals are of the color light type each comprising a plurality of lamps G, Y and R,

which lamps when illuminated indicate clear, caution, and stop, respectively.

Certain of the track sections, namely sections F—H and H—J and other sections (not shown) extending to the right of section H—J, are provided with normally deenergized track circuit apparatus embodying my present invention, while the two other sections D—E and E—F are provided with normally energized track circuit apparatus which operates on the self-generating code principle disclosed in my copending application, Serial No. 443,240. The track circuit apparatus of these latter two sections are arranged to cooperate with the apparatus of the other sections in such manner as to function as starting sections for the remaining sections of the stretch, and the two sections D—E and E—F will be referred to hereinafter as monitor sections.

The track circuit arrangement of the first monitor section D—E comprises two sources of unidirectional energy, designed by the reference characters TB with suitably distinguishing prefixes, and two track relays, designated by the reference characters TR with suitably distinguishing prefixes. Each of the relays TR is a polarity responsive relay of the polar stick type and has an armature operable to one extreme position or another according as the relay is energized by current of one relative polarity or the other.

Relay 1TR has associated therewith three slow releasing relays, designated by the reference characters 1K, 1L and 1N, respectively, and a polar stick relay 1M. Relay 1K is provided with a pick-up circuit which extends from one terminal B of a suitable source of current, such as a battery not shown but having its opposite terminals designated in the drawing by the reference characters B and C, through polar contact 5 closed in the reverse or right-hand position, as viewed in the drawing, of the polar armature of relay 1TR, polar contact 6 closed in the normal or left-hand position of relay 1M, and the winding of relay 1K to terminal C. Relay 1K also is provided with an auxiliary circuit in which front contact 7 of relay 1L provides an alternate path around polar contact 6 of relay 1M. Relay 1L is provided with an energizing circuit which may be traced from terminal B through polar contact 5 of relay 1TR closed in its normal or left-hand position, front contact 10 of relay 1K and the winding of relay 1L to terminal C. Relay 1N is connected through a filter device 1NF across a winding 11 which has one portion or the other thereof supplied with unidirectional energy according as relay 1TR is in its normal or its reverse position, respectively. In the normal position of the relay, a circuit is completed from terminal B through normal polar contact 5 of relay 1TR, front contact 10 of relay 1K and the lower portion (as viewed in the drawing) of winding 11 to terminal C; while in the reverse position of relay 1TR an obvious circuit is completed from terminal B through reverse polar contact 5 of relay 1TR and the upper portion of winding 11 to terminal C. A condenser 12 connected across winding 11 is proportioned to tune the winding to effective resonance at a predetermined frequency hereinafter mentioned, and when the supply of current to winding 11 is periodically reversed at such frequency, relay 1N will be energized.

The relays 1L and 1N control the associated signal 1S in such manner that when both relays are picked up, lamp G of the signal is conditioned to become illuminated over an obvious circuit ex-

tending from terminal B through back contact 14 of a relay OAP, hereinafter to be referred to, front contact 15 of relay 1L, front contact 16 of relay 1N and the filament of lamp G of signal 1S to terminal C; when relay 1N is released but relay 1L is picked up, lamp Y of the signal is conditioned to become illuminated over an obvious circuit extending from terminal B through back contact 14 of relay OAP, front contact 15 of relay 1L, back contact 16 of relay 1N and the filament of lamp Y of signal 1S to terminal C; and when both relays 1N and 1L are released, lamp R of signal 1S is conditioned to become illuminated over a circuit extending from terminal B through back contact 14 of relay OAP, back contact 15 of relay 1L and the filament of lamp R of signal 1S to terminal C. It is to be noted that the lamps of signal 1S are normally dark and will become illuminated only when contact 14 is closed. This contact is operated by relay OAP associated with the track circuit apparatus of the section extending to the left of section D—E, and such relay preferably is controlled by its associated apparatus in a manner substantially corresponding to the manner hereinafter pointed out whereby relay 2AP is controlled by relay 2TR of section D—E.

Relay 1M is a two-winding relay provided with a normal energizing circuit which extends from terminal B through normal polar contact 18 of relay 1TR, and one portion of the winding of relay 1M to terminal C; with a reverse energizing circuit which extends from terminal B through reverse polar contact 18 of relay 1TR, front contact 19 of relay 1K, and the other portion of the winding of relay 1M to terminal C; and with an auxiliary circuit which extends from terminal B through reverse polar contact 18 of relay 1TR, back contact 19 of relay 1K, back contact 20 of relay 1L, and the said one portion of the winding of relay 1M to terminal C.

Relay 2TR is provided with a slow releasing impulse generating relay 2TPR which is normally energized over a circuit which may be traced from terminal B through normal polar contact 21 of relay 2TR, front contact 22 (which has the reference character 3L placed above the contact to indicate that it is controlled by relay 3L associated with the adjoining advance section E—F), the winding of relay 2TPR and to terminal C. Whenever relay 3L is released, then relay 2TPR becomes energized over an obvious circuit including front contact 23 of an auxiliary slow pick-up relay 2HP, which relay is energized over a circuit including the source of current, normal polar contact 21 of relay 2TR, back contact 22 of relay 3L and the winding of relay 2HP. The arrangement is thus such that when relay 3L is picked up, relay 2TPR functions as a straight repeater of relay 2TR and is picked up immediately each time relay 2TR operates to its normal position, but whenever relay 3L is released, the pick-up of relay 2TPR after relay 2TR operates to its normal position is deferred for the full pick-up interval of relay 2HP.

Relay 2TR also has associated therewith a first slow releasing relay 2AP energized over an obvious circuit including reverse polar contact 25 of relay 2TR. Relay 2AP is provided with a slow releasing repeater relay 2APP which is energized over an obvious circuit including front contact 26 of relay 2AP.

The track circuit apparatus of the second monitor section, E—F, is in general similar to that just described for section D—E, except that

at times a shunt or short-circuit path is connected across the rails of section E—F adjacent to end E. This shunt circuit path is completed through back contact 28 of relay 2AP and front contact 29 of relay 2APP, and is effective after relay 2AP releases and while relay 2APP is still held up due to its slow release interval. The shunt circuit path functions in a manner to be made clear presently, to cause energy to be applied to the remaining normally deenergized sections of the stretch.

The track circuit apparatus of the first normally deenergized section F—H, is in general similar to the track circuit apparatus provided for section D—E. However, section F—H is provided with a stick relay 5SR and a stick repeater relay 5SPR. Relay 5SR has a pick-up circuit which extends from terminal B through back contact 30 of relay 4AP, and the winding of relay 5SR to terminal C; and has a stick circuit which passes from terminal B through front contact 31 of relay 5L, front contact 32 and the winding of relay 5SR to terminal C. An alternate stick circuit path for relay 5SR is completed when back contact 30 of relay 4AP and front contact 32 of relay 5SR are closed, respectively. Relay 5SPR has a pick-up circuit which may be traced from terminal B through back contact 31 of relay 5L, front contact 33 of relay 5SR and the winding of relay 5SPR to terminal C. This relay also has a stick circuit in which front contact 34 of relay 5SPR provides an alternate path around front contact 33 of relay 5SR in the previously traced pick-up circuit of the relay.

Relays 5SR and 5SPR function to connect and disconnect relay 5TR from the rails of the associated section. When both relays 5SR and 5SPR are released, relay 5TR and battery 5TB are placed on open circuit, with the result that no closed circuit track circuit can be completed for the section at this time, as will be made clear presently. Whenever relay 5SR closes its front contact 36 and/or relay 5SPR closes its front contact 37, then relay 5TR is connected in circuit with the track rails either alone or in series with battery 5TB, and hence the apparatus of section F—H is then conditioned to provide closed-circuit track circuits for the section.

The relays 5SR and 5SPR also function to control the supply of energy to the decoding relays 5K, 5L, 5M and 5N of section F—H, in such a manner that when both relays 5SR and 5SPR are released, energy cannot be supplied to any of the named decoding relays, but whenever relay 5SR closes its front contact 38 and/or relay 5SPR closes its front contact 39, the apparatus is then conditioned to supply energy to the decoding relays.

The track circuit apparatus of section H—J, and also of the remaining sections (not shown) of the stretch, is substantially similar to the apparatus just described for section F—H, and differs therefrom largely to the extent that the pick-up circuit of relay 7SR is carried through front contact 40 of the associated approach control relay 6AP, while the lamps of signal 7S are supplied with energy when front contact 42 of relay 7SR is closed.

In the normal condition of the apparatus, the stretch of track D—J is unoccupied and the apparatus assumes the condition represented in the drawings. In this condition of the apparatus, relays 1TR and 2TR of section D—E are energized, in series, by energy derived alternately from the two sources TB. Battery 1TB, for

example, energizes both relays 1TR and 2TR in series over a first track circuit extending from one terminal of battery 1TB through normal polar contact 8 of relay 1M, rail 1, front contact 9 of relay 2TPR, the winding of relay 2TR, rail 1a and the winding of relay 1TR to the other terminal of battery 1TB. This track circuit is completed when relay 1M is in its normal position due to the energization of the relay over its normal circuit including normal polar contact 18 of relay 1TR, and when relay 2TPR is energized to close its front contact 9. The polarity of current supplied from battery 1TB to the relays 1TR and 2TR over the first track circuit is such as to cause the relays to shift their respective armatures from the illustrated position to the reverse or right-hand position, whereupon relay 2TPR becomes deenergized, and relay 1M is caused to shift its polar armature to its reverse position, thereby opening or interrupting the first track circuit by disconnecting battery 1TB from the track rails and relays 1TR and 2TR. Relay 2TPR releases, at the end of its release period, and opens its front contact 9 to open the first track circuit at that point. Back contact 9 of relay 2TPR now connects battery 2TB to relays 2TR and 1TR in series over a second track circuit extending from one terminal of battery 2TB through back contact 9 of relay 2TPR, rail 1, reverse polar contact 8 of relay 1M, the winding of relay 1TR, rail 1a, the winding of relay 2TR, and to the other terminal of battery 2TB. The polarity of current supplied from source 2TB to the relays over the second track circuit is the reverse of that supplied from battery 1TB to the first track circuit and causes the relays to shift their respective armatures back to their normal positions, whereupon relay 2TPR becomes energized and immediately picks up to open the second track circuit by disconnecting battery 2TB from the track rails and track relays, while relay 1M becomes energized over its normal circuit and shifts its polar contact member 8 to its normal position. The opening of reverse contact 8 opens the second track circuit and the closing of normal polar contact 8 closes the first track circuit by connecting battery 1TB in circuit with both relays 1TR and 2TR. This cycle of operation continues as long as section D—E is vacant, hence relays 1TR and 2TR are energized in series alternately first by current of one polarity derived from battery 1TB and supplied over a first track circuit and then by current of the opposite polarity derived from battery 2TB and supplied over a second track circuit. Each one of these sources is connected in circuit with the track rails and relays for relatively short intervals of time in response to an impulse of energy received from the other of such sources, with the result that each source of energy is caused to supply coded energy to the rails in response to code impulses of energy supplied from the other of the sources to the rails.

The operation of track relays 1TR and 2TR in response to the self-generated code impulses is detected by means of the associated slow-acting relays 1K, 1L and 1N. Relay 1K, for example, first becomes energized when reverse polar contact 5 of relay 1TR and normal polar contact 6 of relay 1M are closed, and the relay picks up to close its front contact 10 to prepare a circuit for relay 1L, which circuit becomes completed when normal polar contact 5 of relay 1TR closes. When relay 1L picks up, another circuit for relay 1K is prepared, including reverse polar

contact 5 of relay 1TR and front contact 7 of relay 1L, hence when relay 1TR operates its polar armature alternately to first one and then the other position relays 1K and 1L are alternately energized. In addition with relay 1K picked up, polar relay 1M is reversibly energized due to the operation of contact 18 of relay 1TR. The operation of relay 1TR alternately to its normal and reverse positions causes the direction of unidirectional current supplied to winding 11 to be periodically interrupted at a predetermined frequency that is determined largely by the slow release time of relay 2TPR. Condenser 12 and filter unit 1NF are proportioned and adjusted in such manner that relay 1N is at this time effectively energized and picked up. Relays 1K, 1L and 1N are provided with slow releasing periods, attained in part at least by means of resistors 17 connected across their terminals, selected to maintain the relays in their picked-up positions for intervals which bridge the intervals that the respective energizing circuits are open due to the operation of the polar contacts of relays 1TR and 1M. With these relays picked up, signal 1S is conditioned to display its clear aspect and will do so when back contact 14 of relay OAP closes. At this time, relays 2AP and 2APP are picked up since contact 25 of relay 2TR alternately closes and opens to intermittently energize relay 2AP, which relay picks up in turn to energize and pick up relay 2APP.

The track circuit apparatus of section E—F operates in a manner generally similar to that described for section D—E, with the difference that relay 5L of the section in advance (section F—H) is released, hence after relay 4TR operates to its normal position, relay 4TPR will pick up only after relay 4HP picks up at the end of its slow pick-up interval. The slow pick-up period of relay 4HP is thus introduced into and added to the interval between successive impulses of energy from battery 4TB, hence these impulses occur at a frequency substantially lower than the frequency at which impulses are supplied from battery 2TB when relay 3L is picked up. This lower frequency of impulse supply causes operation of relay 3TR at a corresponding frequency and causes relays 3K and 3L to be picked up. Relay 3N is, however, released since at this lower frequency of operation of relay 3TR, winding 11 and condenser 12 do not approach a resonant condition and the energy supplied therefrom to relay 3N is insufficient to pick up that relay. Signal 3S accordingly is conditioned to display its caution aspect and will do so when back contact 14 of relay 2AP closes.

At this time both relays 5TR and 7TR are placed on open circuit since the associated stick and stick repeater relays SR and SPR are released. Relays 5K, 5L and 5N associated with relay 5TR and relays 7K, 7L and 7N associated with relay 7TR are, therefore, released, with the result that signals 5S and 7S are conditioned to display their respective stop aspects but at this time are dark.

When a train operating on the stretch approaches section D—E, relay OAP associated with the section to the left of section D—E will close its back contact 14, whereupon lamp G of signal 1S becomes illuminated and is caused to display its green aspect. This condition of the apparatus obtains until the train enters section D—E, whereupon a train shunt is established in the section and relay 2TR either remains in or assumes its normal position, while relay 1TR

either remains in or assumes its reverse position. In other words, with a train in the section, the two track relays are caused to operate their polar armatures to positions out of correspondence. For example, when a train enters the section when battery 1TB is connected to the track rails, the train shunt established in the section prevents relay 2TR at the opposite section end from responding to such energy, hence relay 2TR 5 remains in its normal position and relay 2TPR is maintained energized. Relay 1TR, on the other hand, becomes energized in series with the train shunt and operates its polar armature to its reverse position, thereby reversing the energization 10 of relay 1M, which relay operates its polar armature in turn to disconnect battery 1TB from the track rails. Relay 1TR remains in its reverse position since no energy impulse of the opposite polarity is at this time impressed on the track 15 rails, and relay 1L first releases to open its front contact 7 whereupon relay 1K also releases. Relay 1M, however, now becomes energized by current of normal polarity over its auxiliary circuit including reverse polar contact 18 of relay 1TR, 20 back contact 19 of relay 1K and back contact 20 of relay 1L, whereupon normal polar contacts 6 and 8 of relay 1M close. Relay 1TR now becomes energized again in series with the train shunt, by current of the polarity corresponding 25 to the reverse position of the relay, but no operation of relay 1TR is effected at this time since the relay already is in its reverse position. Relay 1K, however, picks up over its pick-up circuit including reverse contact 5 of relay 1TR and normal polar contact 6 of relay 1M, and back contact 19 of relay 1K opens to interrupt the previously traced auxiliary circuit for relay 1M. Front contact 19 of relay 1K is now closed to complete the reverse circuit of relay 1M, whereupon 30 the polar contacts of that relay reverse to disconnect battery 1TB from the track rails, and to deenergize relay 1K. When that relay drops, relay 1M again becomes energized by current of normal polarity and shifts its polar contact members 6 and 8. This operation of relays 1M and 1K continues as long as the train shunt is maintained in the section, and has a function which will be pointed out hereinafter.

With relay 2TR held constantly in its normal position by the shunt established by the train in the section, relay 2AP releases to close its back contact 14 to apply energy to the lamps of signal 3S, and to open its front contact 26 and thereby deenergize relay 2APP. Relay 2APP is held up, 50 however, due to the slow releasing characteristics and at this time the previously traced shunt circuit path is applied across the rails of section E—F. This circuit includes back contact 28 of relay 2AP and front contact 29 of relay 2APP, and it functions much in the same manner as if a train shunt were established across the track rails. That is to say, energy from battery 3TB 55 is shunted away from relay 4TR so that relay 4TR either remains in or assumes its normal position, while relay 3TR either remains in or assumes its reverse position. Relays 3M and 3K are now caused to interact and operate to cause relay 3M to intermittently apply impulses of energy to the track rails. These impulses are at this time shunted away from track relay 4TR by the shunt circuit path, hence no operation of relay 4TR will be effected and as a result relay 4AP is caused to release since its energizing circuit is held open when relay 4TR is in its normal position, and back contact 30 of relay 4AP closes to energize 60 65 70 75

relay 5SR. Relay 5SR accordingly picks up and closes its front contact 36 to connect relay 5TR and battery 5TB in circuit with the track rails of section F—H, whereupon relays 5TR and 6TR become energized in series with battery 5TB and the apparatus of section F—H is conditioned to reversibly operate relays 5TR and 6TR in a manner corresponding to that hereinbefore pointed out in connection with section D—E. Front contact 38 of relay 5SR is now closed and relays 5K, 5L and 5M accordingly are supplied with energy and are caused to pick up in response to the operation of relay 5TR, whereupon signal 5S is conditioned to display its caution aspect, and when relay 5L picks up, the stick circuit of relay 5SR is completed at front contact 31 of relay 5L. Additionally, relay 6AP is caused to pick up when relay 6TR operates to its reverse position, and relay 6AP in turn picks up relay 7SR, whereupon that relay closes its front contact 36 to connect relay 7TR and battery 7TB in circuit with the rails of section F—H. Relays 7TR and 8TR thereupon become energized and are caused to operate in substantially the same manner that relays 1TR and 2TR are caused to operate. Front contact 38 of relay 7SR is closed and, with relay 7TR reversibly operated, relays 7K, 7L and 7M are picked up with the result that front contact 22 of relay 7L closes to cause relay 6TPR to function as a straight repeater relay of relay 6TR, whereupon relay 5N is caused to pick up and signal 5S accordingly is conditioned to display its clear aspect. Additionally, relay 8AP picks up to condition the track circuit apparatus of the section in advance of section H—J to apply energy to the track circuits thereof, and I shall assume that this apparatus (not shown) is effective to cause front contact 22 of relay 9L to close and in turn shift the frequency at which energy impulses are supplied from battery 8TB to the track rails. When this happens, relay 7N is picked up and signal 7S is conditioned to display its clear aspect and does so since its energizing circuit is now complete at front contact 42 of relay 7SR.

At the end of the slow release interval of relay 2APP, that relay releases to open its front contact 29 and thereby open the shunt circuit applied across the rails of section E—F. When this happens, the first impulse of energy that is applied to the rails of section E—F due to the interaction of relays 3K and 3M causes relay 4TR to operate to its reverse position, whereupon relay 4AP picks up, and relay 4TPR releases, thereby causing the track circuit apparatus of section E—F to be restored to its normal condition in a manner to be explained in detail hereinafter. In this restored condition of the apparatus of section E—F, the two track relays 3TR and 4TR are caused to be reversibly energized first by energy supplied from battery 4TB and then from battery 3TB. At this time, relay 5L is picked up, so that relay 4TPR functions as a straight repeater relay for relay 4TR and as a result relays 3K, 3L, 3M and 3N associated with relay 3TR are picked up. Signal 3S accordingly is conditioned to display its clear aspect and does so at this time due to the fact that back contact 14 of relay 2AP is closed and connects energy to the lamps of signal 3S.

From the foregoing description, it is readily apparent that when a train approaches signal 1S, it will receive a clear aspect if conditions in advance warrant the display of this aspect. When the train enters the section (D—E) gov-

erned by signal 1S, a shunt is momentarily applied to the track circuit apparatus of advance section E—F, whereupon that apparatus functions to cause energy to be applied to each of the normally deenergized sections in advance of section E—F. If this happens when traffic conditions in these advance sections are favorable, each of the advance signals is conditioned to display its clear indication, and relay 5L associated with section F—H picks up to condition the track circuit apparatus of section E—F to apply clear track circuit code to the rails of the associated section. This clear track circuit becomes effective after the momentarily applied shunt on relay 3TR is removed, to cause signal 3S to display its clear aspect if traffic conditions permit. It follows, that the apparatus is so arranged that when a train approaches the normally deenergized sections, such train will cause energy to be applied to the sections prior to arriving thereto, and if traffic conditions so permit, the train will receive clear signal aspects in each of the monitor sections.

When the train enters section E—F, both relays 3TR and 4TR are shunted and such relays assume their occupied section positions hereinbefore described wherein relay 4TR is held constantly in its normal position while relay 3TR is held constantly in its reverse position. Relays 3L and 3N accordingly release to cause signal 3S to display its stop aspect, while relays 3K and 3M are caused to be intermittently energized and de-energized and relay 3M functions to intermittently connect battery 3TB to the track rails. These current impulses are, of course, shunted by the train away from relay 4TR, hence relay 4TR remains constantly in its normal position while relay 3TR is held constantly in its reverse position.

As pointed out hereinbefore, when the train occupies section D—E the relays 1K and 1M are caused to interact in such manner as to intermittently apply impulses of energy from battery 1TB to the track rails. These relays 1K and 1M in applying such impulses of energy function as code initiating means effective after the section becomes vacant to restore the apparatus of the section to its normal condition wherein the code impulses supplied to the two track circuits of the section are each caused to be generated by the action of the code impulses supplied to the other circuit. This restoration is effected when the train vacates section D—E and the energy applied by battery 1TB to the track rails, when relay 1M is in its normal condition, is no longer shunted away from relay 2TR. Under such assumed conditions, relay 2TR operates its contact 15 to its right-hand position to deenergize relay 2TPR. That relay in turn releases to open the previously mentioned first track circuit, and to close its back contact 9 to connect battery 2TB and relay 2TR to the track rails. The second track circuit may not at this time be completed since contact 8 of relay 1M will be held in its left-hand position until relay 1K releases. When this happens, the reverse energizing circuit for relay 1M is completed and contact 8 is operated to its right-hand position wherein the second track circuit is completed. At this time, relays 1TR, 2TR and 1M occupy corresponding relative positions and the energization of the track relays cause their contacts to be operated in agreement to the left-hand position. Relay 3L is now deenergized and its back contact 22 is closed, hence relay 2HP becomes energized and

at the end of its slow pick-up period that relay closes its front contact 23 to energize relay 2TPR and cause that relay to close its front contact 9 to complete the second track circuit, and when relay 1M operates to its left-hand position, its contact 8 is in its reverse position and thereby completes the first track circuit. The two track relays accordingly are caused to be reversibly operated over the two track circuits and this operation of relay 2TR is detected by relays 2AP and 2APP, which relays pick up, while the operation of relay 1TR is detected by relays 1K and 1L, which relays also pick up. Relay 1N does not, however, pick up at this time since the slow pick-up period of relay 2HP is introduced into the interval that exists between successive connections of battery 2TB to the track rails, hence the frequency of such connections is relatively low and is insufficient to cause relay 1N to be effectively energized. At this time, signal 1S is conditioned to display its caution indication and will do so only if back contact 14 of relay OAP is closed.

When the train enters section F—H, both relays 5TR and 6TR are shunted, and relays 5L, 5N and 6AP release. Back contact 40 of relay 6AP completes a previously traced stick circuit for relay 1SR, while relay 5SR is now held energized over its pick-up circuit including back contact 30 of relay 4AP. When relay 5L drops it completes the previously traced pick-up circuit of relay 5SPR with the result that relay 5SPR picks up and closes its front contact 34 to complete its stick circuit. Relays 5K and 5M are now intermittently energized and relay 5M operates its contact member 8 intermittently to its left-hand position to apply at times energy to the rails of the associated section. This energy is shunted away from relay 6TR by the train in the section.

When the train vacates section E—F, the first pulse of energy transmitted from battery 3TB over contact 8 of relay 3M and the rails of section E—F to relay 4TR causes the track circuit apparatus of section E—F to reversibly energize relays 3TR and 4TR in substantially the same manner as was pointed out in detail for the operation of the apparatus of section D—E. Relay 4AP is caused to pick up in response to relay 4TR operating intermittently to its reverse position, and when relay 4AP picks up, it opens the pick-up circuit of relay 5SR, whereupon that relay releases and opens its front contact 32 prior to the closing of front contact 30 of relay 4AP. Relay 5SPR is at this time held energized over its stick circuit and this relay functions to maintain the supply of energy to the decoding relays associated with relay 5TR and to the first track circuit of section F—H. At this time, however, relay 5TR is shunted and relay 5L accordingly is released, hence the slow pick-up period of relay 4HP is added into the intervals that exist between successive connections of battery 4TB to the track rails of section E—F, and relays 3K and 3L are energized by the operation of relay 3TR, but relay 3N is not at this time picked up. Signal 3S accordingly is conditioned to display its caution aspect. The track circuit code that is supplied from battery 2TB to the track rails is now shifted to the clear code frequency since with relay 3L picked up, the slow pick-up period of relay 2HP is excluded from the intervals existing between successive connections of battery 2TB to the rails. Relay 1N associated with relay 1TR accordingly picks up to condition signal 1S to display its clear aspect.

When the train enters section H—J, both relays 7TR and 8TR are shunted and these relays assume their respective occupied section positions. Relays 7L and 7N release to set signal 1S at stop; relay 1SPR is picked up over its pick-up circuit including back contact 31 of relay 7L; relays 7K and 7M are alternately energized and relay 7M operates intermittently to impress battery 7TB across the track rails; and relay 8AP also releases.

After the train vacates section F—H, relay 6TR responds to the first energy impulse that is applied to the rails of the section when relay 5M is caused to operate to its normal position, and relay 6TR in turn operates to its reverse position whereupon relay 6AP picks up while relay 6TPR releases and connects battery 6TB to the track rails in circuit with relays 5TR and 6TR. Relay 6TR operates to its normal position, while relay 5TR operates to its normal position and energizes relays 5K and 5M. Battery 5TB is then connected to the track rails to operate relays 5TR and 6TR to their respective reverse positions, whereupon relay 6TPR releases and back contact 9 closes to establish the second track circuit which is effective to operate relays 5TR and 6TR to their normal positions; relay 5L picks up; and the stick circuit of relay 5SPR is interrupted at back contact 31 of relay 5L. Relay 5SPR accordingly releases to place relay 5TR on open circuit, and to remove energy from the decoding relays 5K, 5L, 5M and 5N associated with relay 5TR. The other track relay 6TR remains in its normal position and its associated relay 6TPR becomes energized and is maintained picked up since contact 21 of relay 6TR is held closed in its normal position.

The track circuit apparatus of section H—J likewise is restored to its normally deenergized condition when a train vacates the circuit. The operation of this apparatus at this time is similar to that just described for section F—H, and further detailed description of the operation is deemed unnecessary.

From the foregoing description, it is readily apparent that the apparatus embodying my invention is arranged to apply energy to a track circuit only when a train approaches a circuit, and is maintained on the circuit to restore the track circuit to its normal condition when a train vacates a circuit, whereupon the energy is removed from the circuit. It thus follows that the arrangement of the apparatus avoids the use of energy at all times except when the energy has the particularly useful function of establishing a control for a train approaching these sections. In this manner the supply of energy is conserved, and the wear on the contact apparatus that would normally be occasioned by constantly operating coding elements is eliminated.

In addition, it is apparent that the track circuit arrangement is such that the normally deenergized track circuits when supplied with energy, are effective to code such energy in accordance with traffic conditions in advance, and also are effective to provide means whereby approach energization of the lamps of the signals is attained through the track rails and the use of line wires customarily extended between the opposite ends of a track section, is obviated.

Although I have herein shown and described only one form of railway traffic controlling apparatus embodying my invention, it is understood that various changes and modifications may be made therein within the scope of the appended

claims without departing from the spirit and scope of my invention.

Having thus described my invention, what I claim is:

1. In combination, a section of railway track, a first track relay and a first track battery at one end of said section, a second track relay and a second track battery at the opposite end of said section, both of said track batteries and one of said track relays being normally disconnected from the rails of said section, a first means effective when active for connecting said first and second relays in circuit with the rails of said section and said first track battery, means responsive to traffic approaching said section for rendering active said first means, means responsive to energization of said first and second track relays from said first track battery for disconnecting said first and second relays from said first track battery and for connecting such relays in circuit with the track rails and said second track battery, means responsive to the energization of said first and second track relays from said second track battery for reconnecting said first and second relays in circuit with the track rails and said first track battery, means responsive to traffic in said section for maintaining active said first means, and means responsive to operation of said first relay for governing traffic on said section.

2. In combination, a stretch of railway track including a track section, means for governing traffic operating in a given direction in said section, energy applying means, means responsive to traffic approaching said section in said given direction for rendering active said energy applying means, two sources of unidirectional energy one for each end of said section and each normally disconnected from the rails of said section, two polar relays one for each section end and each having a polar armature, means rendered effective by said energy applying means when active for simultaneously energizing both said relays over a circuit including the rails of said section and alternately first one and then the other of said two current sources, said two current sources being poled in such manner that current from one of the sources causes the two relays to operate their polar armatures to one position and current from the other source causes the relays to operate their armatures to the other position, means governed by traffic in said section for maintaining active said energy applying means, and means governed by the relay at the section end entered by a train operating in said given direction for controlling said traffic governing means.

3. In combination, a stretch of railway track including a track section, a stick relay provided with a pick-up circuit completed when a train approaches said section in a given direction and within a given zone, two sources of unidirectional current one for each end of said section, two polar relays one for each section end and each having a polar armature, means rendered effective when and only when said stick relay is picked up for simultaneously energizing both said polar relays over a circuit including the rails of said section and alternately first one and then the other of said two current sources, said two current sources being poled in such manner that current from one of said sources causes the two polar relays to operate their polar armatures to one position and current from the other source causes the polar relays to operate their armatures

to the other position, and a stick circuit for said stick relay governed by the one polar relay at the section entering end and completed when said one polar relay is reversibly energized.

4. In combination, a stretch of railway track including a track section, a stick relay provided with a pick-up circuit completed when a train operating on said stretch in a given direction approaches within a given zone of said section, 10 two sources of unidirectional current one for each end of said section, two polar relays one for each section end and each having a polar armature, circuit means for simultaneously energizing both said polar relays over a circuit including in series the windings of both of said relays and a front contact of said stick relay and the rails of said section and alternately first one and then the other of said sources, said two sources being poled in such manner that current from one of said sources causes the two polar relays to operate their polar armatures to one position and current from the other source causes the polar relays to operate their polar armatures to another position, and means governed by at least one of said polar relays for establishing a stick circuit for said stick relay when said polar relays are caused to be reversibly operated.

5. In combination, a stretch of railway track including two track sections, a track circuit for 30 one of said sections comprising two current sources one for each end of the section and two polar relays one for each section end and means for simultaneously energizing both said polar relays over a circuit including in series the windings of said polar relays and the rails of said section and alternately first one and then the other of said sources, said sources being oriented in such manner that current from one source causes operation of said polar relays in one direction and current from the other source causes 35 operation of said polar relays in the other direction, means controlled by one of said polar relays for governing traffic in said one section, approach control means governed by the other of said polar relays, track circuit apparatus for the other of said sections comprising two current sources one for each end of said other section and two polar relays one for each of said other section ends, circuit means controlled by said approach control 40 means to be effective when said one section is occupied by a train for simultaneously energizing both of the polar relays of said other section over a circuit which includes in series the windings of both of said polar relays of said other section and the rails of said other section and alternately first one and then the other of the 45 said two sources of said other section, said sources of said other section being oriented in such manner that current from one of such sources causes both of the associated polar relays to operate in one direction and current from the other of such sources causes both of the associated polar relays to operate in another direction, and means governed by one of said polar relays of said other section for governing traffic in said other section.

6. In combination, a stretch of railway track including two track sections, two current sources one for each end of one of said sections and two polar relays one for each end of said one section, 50 means for simultaneously energizing both said relays over a track circuit including in series the windings of said polar relays and the rails of said one section and alternately first one and then the other of said current sources, said sources being oriented to reversibly operate said two polar re-

lays, means controlled by one of said polar relays for governing traffic in said one section, approach control means governed by the other of said polar relays, two other current sources one for each end of the other of said two sections and two other polar relays one for each end of said other section, means controlled by said approach control means to be effective when a shunt path is established across the track circuit of said one section for simultaneously energizing both of said other polar relays over a track circuit including in series the windings of said other polar relays and the rails of said other section and alternately first one and then the other of said other two sources, said other sources being oriented to reversibly operate said other polar relays, and means governed by one of said other polar relays for modifying the control established by said one polar relay over said traffic governing means.

7. In combination, a stretch of railway track including two track sections, two current sources one for each end of one of said sections and two polar relays one for each end of said one section, means for simultaneously energizing both said relays over a track circuit including in series the windings of said polar relays and the rails of said one section and alternately first one and then the other of said current sources, said sources being oriented to reversibly operate said two polar relays, means controlled by one of said polar relays for governing traffic in said one section, approach control means governed by the other of said polar relays, two other current sources one for each end of the other of said two sections and two other polar relays one for each end of said other section, means controlled by said approach control means to be effective when a shunt path is established across the track circuit of said one section for simultaneously energizing both of said other polar relays over a track circuit including in series the windings of said other polar relays and the rails of said other section and alternately first one and then the other of said other two sources, said other sources being oriented to reversibly operate said other polar relays, means controlled by one of said other polar relays for governing traffic in said other section, and other means governed by said one other polar relay for modifying the control established by said one polar relay over its said associated traffic governing means.

8. In combination, a stretch of railway track including two track sections, two current sources one for each end of one of said sections and two polar relays one for each end of said one section, means for simultaneously energizing both said relays over a track circuit including in series the windings of said polar relays and the rails of said one section and alternately first one and then the other of said current sources, said sources being oriented to reversibly operate said two polar relays, means controlled by one of said polar relays for governing traffic in said one section in accordance with the rate of reversible operation of said one polar relay, approach control means governed by the other of said polar relays, two other current sources one for each end of the other of said two sections and two other polar

relays one for each end of said other section, means controlled by said approach control means to be effective when a shunt path is established across the track circuit of said one section for simultaneously energizing both of said other polar relays over a track circuit including in series the windings of said other polar relays and the rails of said other section and alternately first one and then the other of said other two sources, said other sources being oriented to reversibly operate said other polar relays, and means governed by one of said other polar relays for controlling the rate at which the polar relays of said one section are reversibly operated.

9. In combination, a stretch of railway track including two track sections, two current sources one for each end of one of said sections and two polar relays one for each end of said one section, means for simultaneously energizing both said relays over a track circuit including in series the windings of said polar relays and the rails of said one section and alternately first one and then the other of said current sources, said sources being oriented to reversibly operate said two polar relays, means controlled by one of said polar relays for governing traffic in said one section in accordance with the rate of reversible operation of said one polar relay, approach control means governed by the other of said polar relays, two other current sources one for each end of the other of said two sections and two other polar relays one for each end of said other section, means controlled by said approach control means to be effective when a shunt path is established across the track circuit of said one section for simultaneously energizing both of said other polar relays over a track circuit including in series the windings of said other polar relays and the rails of said other section and alternately first one and then the other of said other two sources, said other sources being oriented to reversibly operate said other polar relays, means controlled by one of said other polar relays for governing traffic in said other section and rendered effective by said approach control means, and means governed by said one other polar relay for controlling the rate of reversible operation of the polar relays of said one section.

10. In combination, a stretch of railway track including a plurality of successive adjoining track sections, means for providing normally energized closed circuit track circuits for the two sections of said stretch first to be traversed by a train operating in a given direction over said stretch, means rendered effective when the first encountered one of said two sections is occupied by a train for applying a shunt momentarily across the rails of the second of said two track sections, means rendered effective when said momentary shunt is applied to said second section for providing each of the remaining sections of track with a closed circuit track circuit, and means rendered effective by the track circuit of each of said other sections for maintaining such track circuit after said momentary shunt is removed and until the section is traversed by the train.

JOHN M. PELIKAN.
